(57) **CLAIM**

The ornamental design for charging base tray for flameless candles, as shown and described.

DESCRIPTION

FIG. 1 is a front perspective view of a charging base tray for flameless candles showing our new designs;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof shown in use;

FIG. 10 is another perspective view thereof shown in use; and,

FIG. 11 is another perspective view thereof shown in use. The broken lines in the Figures show portions of the charging base tray for flameless candles which form no part of the claimed design.

1 Claim, 7 Drawing Sheets
